(57) **CLAIM**

The ornamental design for a portable device for transferring fluids, as described and shown in the various figures of the drawings.

DESCRIPTION

FIG. 1 is a perspective view of a housing of the present invention;

FIG. 2 is a left side elevational view of the housing of the present invention shown in FIG. 1;

FIG. 3 is a right side elevational view of the housing of the present invention shown in FIG. 1;

FIG. 4 is a front elevational view of the housing of the present invention shown in FIG. 1;

FIG. 5 is a bottom plan view of the housing of the present invention shown in FIG. 1;

FIG. 6 is an end elevational view of the housing of the present invention shown in FIG. 1; and,

FIG. 7 is a top plan view of the housing of the present invention shown in FIG. 1.
